ATTORNEY

UNITED STATES PATENT OFFICE.

AMASA C. WILLIAMS, OF FAIRFAX, ALABAMA.

MOP.

Application filed November 15, 1921. Serial No. 515,342.

To all whom it may concern:

Be it known that I, AMASA C. WILLIAMS, a citizen of the United States, residing at Fairfax, in the county of Chambers and State of Alabama, have invented new and useful Improvements in Mops, of which the following is a specification.

This invention relates to improvements in mops and has particular relation to novel means for securing the mop element or absorbent material to the mop handle, in a convenient and positive manner, the said means acting to prevent contact of the end of the handle with the floor or other surface and to prevent marring of the woodwork or furniture.

Another object is the provision of securing means of this character which is simple and cheap of construction and which may be easily applied.

With the above and other objects in view, the invention further includes the following novel features and details of construction, to be hereinafter more fully described, illustrated in the accompanying drawings and pointed out in the appended claim.

In the drawings:—

Figure 1 is an elevation of a mop constructed in accordance with the invention.

Figure 2 is an enlarged sectional view on the line 2—2 of Figure 1.

Figure 3 is a detail view of the mop handle with the securing collar attached thereto.

Figure 4 is an end view of the same.

Figure 5 is a view showing the manner of securing the mop element to the handle, the said element being shown in its position prior to the final folding of the same.

Referring to the drawings in detail, wherein like characters of reference denote corresponding parts, the reference character 10 indicates a handle which is herein shown as formed of wood. Secured to one

end of the handle is a split ring 11 which is arranged concentrically of and spaced from the said handle and for this purpose

is provided with an inwardly extending arm 13 which terminates in a penetrating member 14 which is driven or otherwise positioned centrally of the end of the arm. The ferrule 15 surrounds this end of the handle so as to prevent the latter from splitting.

The mop element which is indicated at 16 may be made of cloth, yarn, fiber or any suitable material and is passed through the collar 11 and secured within the receiving spaces 17 formed between the collar and the adjacent end of the handle, by means of a tie 18. This forces the mop material within this receiving space, while an additional tie 19 surrounds the mop material upon the opposite side of the collar. The material is then folded over around the collar 11 and secured in place by an additional tie 20 so as to provide a finished mop as shown in Figure 1 of the drawings.

The invention is susceptible of various changes in its form, proportions and minor details of construction and the right is herein reserved to make such changes as properly fall within the scope of the appended claim.

Having described the invention what is claimed is:—

A mop comprising a handle, a collar secured to and spaced from one end of the handle and providing a receiving space between the handle and collar, an absorbent element extending through and upon the outside of the collar, a tie secured around the absorbent material between the collar and the adjacent end of the handle for forcing and securing the material within the receiving space at a point intermediate the ends of said absorbent material, a second tie secured around the absorbent material, and an element passing around the absorbent material to retain the same in folded position about the outer end of the collar.

In testimony whereof I affix my signature.

AMASA C. WILLIAMS.
